UNITED STATES PATENT OFFICE.

WILLIAM H. SOMERS, OF NEW YORK, N. Y.

CHILD'S WAIST.

Application filed November 18, 1921. Serial No. 516,102.

To all whom it may concern:

Be it known that I, WILLIAM H. SOMERS, a citizen of the United States, and residing at New York city, New York County, State 5 of New York, have invented certain new and useful Improvements in Children's Waists, of which the following is a specification.

This invention relates to a child's waist of the type known as slip on waist which 10 does not open back, front or anywhere longitudinally, but is merely slipped on over the child's body and thus is composed of continuous material circumferentially. The present invention is designed to produce 15 such a waist embodying adjusting means by which the effective size of the waist may be changed and thus it may be enlarged as the child grows so as to properly fit and he may wear it longer than he otherwise could. It 20 furthermore has another advantage from the commercial standpoint since it enables dealers to fit customers more easily and avoids the necessity for carrying so many sizes in stock. The adjusting means is placed at the 25 lower portion of the back of the waist. The slip on feature also has the advantage of reducing the number of buttons necessary, makes it easier to put on, and makes the adjustment more satisfactory. The novel features 30 will be fully understood from the following description and claims taken with the drawings. In the drawings:

Fig. 1 is a rear view of a waist embodying the invention with the parts adjusted 35 to the smaller size; and

Fig. 2 is a similar view showing the adjusting strap loose and drawn back to more clearly illustrate the structure beneath.

As shown in the drawings the body portion 40 of the waist is formed of any suitable fabric which is continuous around the body portion with no dividing line with edges to be connected by buttons. It has shoulder straps 11 leaving a neck opening 12 between them and arm holes 13. It may be provided with strengthening strips 14 sewed to its outer surface extending up over the shoulder straps and with parallel strengthening strips 15 and 16 around it near the 45 lower end. A portion of the material at the central part of the lower edge in the back is removed, as shown at 17, up to and through strengthening strip 15. A flap or tab 18 preferably integral with the material

of the body connects at one end with the 55 body at one side edge of the opening formed where the material is removed at 17 and in Figure 2 is shown folded back exposing the opening. It is wide enough to cover the opening and has in it two pairs of button 60 holes 19 and 20 the pairs being spaced longitudinally and those of a pair being in vertical alignment. Between the strip 15 and the lower edge on the opposite side of the opening 17 two pairs of buttons 21 and 22 are 65 secured. The length of strap 18 and the relative positions of the button holes in it and the buttons on the other side are such that when the flap is folded to the position shown in Figure 1 the buttons 22 may enter 70 button holes 20 and buttons 21 enter button holes 19. When thus connected the end of tab 18 where it connects with the body portion at the side of opening 17 is in approximately the same vertical line as the edge of 75 the body fabric on the opposite side of opening 17 and the fabric of the body immediately above opening 17 is folded to a certain extent. This is the contracted condition of the garment and is the proper condition for 80 sale and for purchase for a growing child. The waist may then be enlarged by unbuttoning the flap 18, moving it outwardly and causing buttons 21 only to enter and engage button holes 20. The amount of the enlargement 85 will correspond to the distance between the pairs of button holes 19 and 20. Vertical strengthening strips 23 may be used adjacent and between the pairs of buttons 21 and 22 and similar strips 24 may be used between 90 and adjacent to button holes 19 and 20 in flap 18.

Although one specific embodiment of the invention is shown for purposes of illustration, the invention is not limited to that particular form beyond what is indicated in the claims.

Having thus described the invention what is claimed as new and desired to be secured by Letters Patent is:

1. A slip-on child's waist composed of fabric permanently continuous around the body portion and means at the lower portion only for adjusting its size including two pairs of laterally spaced vertically aligned buttons and a flap connected to the body portion at one end and having two pairs of vertically aligned longitudinally spaced button

holes corresponding in spacing and position with said buttons and adapted to be entered and engaged by said buttons.

2. A slip-on child's waist composed of fabric permanently continuous around the body portion having a portion removed from the bottom edge upwardly for a short distance forming a notch or opening, two pairs of vertically aligned laterally spaced buttons on one side of said opening and a flap connected at one end to the body on the opposite side of said opening and provided with two pairs of vertically aligned longitudinally spaced button holes corresponding in spacing and relation to said buttons whereby the end pair of button holes may be entered and engaged by either pair of buttons thus effecting an adjustment of the size of the waist.
- 20 3. A slip-on child's waist composed of fabric permanently continuous around the body portion and means at the lower central portion only of its back for adjusting its size including two pairs of laterally spaced vertically aligned buttons on one side of the center line near the bottom at the back and

a flap connected to the body portion at one end and having two pairs of vertically aligned longitudinally spaced button holes corresponding in spacing and position with said buttons and adapted to be entered and engaged by said buttons.

- 30 4. A slip-on child's waist composed of fabric permanently continuous around the body portion having a portion centrally of the back removed from the bottom edge upwardly for a short distance forming a notch or opening, two pairs of vertically aligned laterally spaced buttons on one side of said opening and a flap connected at one end to the body on the opposite side of said opening and provided with two pairs of vertically aligned longitudinally spaced button holes corresponding in spacing and relations to said buttons whereby the end pair of button holes may be entered and engaged by either pair of buttons thus effecting an adjustment of the size of the waist.

35 40 45 In testimony whereof I hereunto affix my signature.

WILLIAM H. SOMERS.
